CLAIM

The ornamental design for a knife handle, as shown and described.

DESCRIPTION

FIG. 1 is a bottom view of an embodiment of a knife handle according to the invention;

FIG. 2 is a top view of the knife handle of FIG. 1;

FIG. 3 is a side view of the knife handle of FIG. 1;

FIG. 4 is a front end view of the knife handle of FIG. 1;

FIG. 5 is a rear end view of the knife handle of FIG. 1; and, FIG. 6 is a front perspective view of the knife handle of FIG. 1.

The knife blade and other portions shown in broken lines are for illustrative purposes only and form no part of the claimed design.
